UNITED STATES PATENT OFFICE

158,546

PERFUME CONTAINER BROOCH

Paul Bardach, Providence, R. I.

Application July 20, 1949, Serial No. 4,015

Term of patent 3½ years

(Cl. D45—19)

To all whom it may concern:

Be it known that I, Paul Bardach, a citizen of the United States, residing at Providence, in the county of Providence, and State of Rhode Island, have invented a new, original, and ornamental Design for a Perfume Container Brooch, of which the following is a specification, reference being had to the accompanying drawing, constituting a part hereof.

Fig. 1 is a top plan view of a perfume container brooch, showing my new design;

Fig. 2 is a side view thereof; and

Fig. 3 is a bottom view thereof.

I claim:

The ornamental design for a perfume container brooch, substantially as shown.

PAUL BARDACH.
